UNITED STATES PATENT OFFICE.

CHARLES M. POWERS, OF DUBOIS, PENNSYLVANIA.

TOOL-HANDLE.

SPECIFICATION forming part of Letters Patent No. 377,688, dated February 7, 1888.

Application filed October 10, 1887. Serial No. 251,968. (No model.)

To all whom it may concern:

Be it known that I, CHARLES M. POWERS, a citizen of the United States, residing at Dubois, in the county of Clearfield and State of Pennsylvania, have invented certain new and useful Improvements in Tool-Handles; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to tool-handles, and aims to produce a handle which will hold different sizes of tools, and which can readily be detached from one tool and quickly applied to another, and when so applied cannot become detached accidentally.

The improvement consists in the clamping devices for securing the tool in the handle and the provisions for supporting the clamping devices, and the means for securing the parts of the handle together.

The improvements further consist in the peculiar construction and combination of the parts, which will be more fully hereinafter set forth and claimed, and shown in the accompanying drawings, in which—

Figure 1 is a longitudinal sectional view of the handle, showing the handle in position; Fig. 2, an edge view of the tool-clamping device and the tool removed from the handle; Fig. 3, a side view of the handle and tool, showing the end of the handle detached; Fig. 4, an end view of the handle; and Fig. 5, a detail perspective view of the shank of the tool and the tool-clamping device, showing the parts detached and in their relative position.

The tool-handle is made in two parts, A and A', which are fitted together by a scarf-joint. (Shown most clearly in Fig. 1.) The end of the part A is recessed and the approximate end of the part A' has a corresponding projection, a, which, fitting in the recessed end of the part A, prevents the parts A and A' from lateral displacement when held together. The part A has a bore, C, and diametrically-opposite longitudinal grooves d, which receive a portion of the tang e of the tool E and the ends of the plates or cross-head f, between which

the catches G are pivoted. The part A' has a corresponding bore, C', which is enlarged at the outer end of the handle, and receives the nut H, which is forced in the enlarged portion 55 of the bore C', and is designed to receive the threaded stem I, which is provided with the plates F, fastened to its inner end. These plates extend parallel with each other and have the cross-plates f at their outer ends, which, as 60 previously mentioned, have the catches G pivoted between them.

The catches G are sufficiently long to incline inward and have their ends meet, or nearly meet, so as to fit in the notches e' in the edges 65 of the tang and grip it, and they are held in engagement with the tang by the spring J, which surrounds the plates F and bears on the catches between their pivotal supports i and their inner ends. To release the catches from 70 the tang of the tool, they have extensions g, which afford a purchase for the fingers. Now by pressing upon the extensions g the inner ends of the catches will be forced outward and permit the disengagement of the tool from the 75 clamping devices.

To adjust a tool, the parts A and A' are separated by unscrewing the end A' and clamping device removed from the part A. The tang is pressed between the catches until they enter 80 the notches in the edges of the tang. Now the shank with the clamping device attached is inserted in the part A from the ferruled end m until the threaded stem I protrudes from the opposite end, as shown in Fig. 3. Now the 85 end A' is screwed on the said stem I until the parts A and A' are held together with sufficient tension. To disengage the tool, the reverse of this operation is performed, the end A' is unscrewed, the tool and the clamping device removed from the part A, and the ends g of the catches G pressed together, so as to disengage the catches, as hereinbefore more particularly described.

Having thus described my invention, what I 95 claim, and desire to secure by Letters Patent, is—

1. The herein-described tool-handle, composed of the two parts, having the end of one part recessed and the approximate end of the other part correspondingly raised and each part longitudinally bored, the one having longi-

- tudinal grooves diametrically opposite to each other, the nut located within the bore of the other part, the threaded stem, the plates having cross-heads, the catches pivoted between 5 the ends of the cross-heads of said plates, the extensions projecting from the catches, and the spring for pressing the ends of the catches together, substantially as and for the purpose described.
- 10 2. The combination, with the tool-handle having a bore, of the catches pivotally supported between their ends on diametrically-opposite sides of the bore, and having their inner ends adapted to grip the tang of a tool, the coil-spring J, constructed and arranged to exert a pressure on said catches to one side of their pivotal supports for pressing the ends of the catches together, and the extensions g, substantially as and for the purpose described.
- 15 3. The combination, with the tool-handle having a bore and longitudinal grooves diametrically opposite to each other, of the plates F, for supporting the tool-clamping devices located in the bore, each plate having a cross-head and the ends of the cross-heads working 20 in the said longitudinal grooves, the catches

pivoted between the ends of the cross-heads to grip the sides of a tool-tang between their inner ends, and having extensions which work in the said longitudinal grooves, and the spring 30 35 for advancing the inner ends of the catches together, substantially as specified.

4. The combination, with the tool-handle made of two parts, A and A', the part A having a bore and longitudinal grooves d, the part A' having a bore, C', which is enlarged at its outer end, and the nut fitted in the enlargement of bore C', of the threaded stem adapted to screw into said nut, the plates F, having cross-heads f secured to the stem, the catches 40 45 having extensions pivoted between the ends of the cross-heads, and the spring J, surrounding the plates and bearing against the catches between their inner ends and their pivotal supports, substantially as and for the purpose specified.

In testimony whereof I affix my signature in presence of two witnesses.

CHARLES M. POWERS.
